UNITED STATES PATENT OFFICE.

ALBERT E. PECKHAM, OF GRAND RAPIDS, MICHIGAN.

BOOT AND SHOE HEEL.

Application filed December 3, 1923. Serial No. 678,176.

To all whom it may concern:

Be it known that I, ALBERT E. PECKHAM, citizen of the United States, residing at Grand Rapids, in the county of Kent and State of Michigan, have invented certain new and useful Improvements in Boot and Shoe Heels, of which the following is a specification.

My invention relates to improvements in boot heels, and its objects are: first, to provide a means whereby a rubber heel may be secured to the leather heel lifts upon a boot or shoe in such a manner as to avoid the danger of a crack showing between the 15 rubber heel and the leather lifts; second, to provide a means whereby the nails that secure a rubber heel to the leather lifts will be prevented from being forced up into the heel of the wearer of a shoe equipped with 20 my invention, and, third, to provide a means whereby the danger of the rubber heel being severed from the lifts is reduced to a minimum.

I attain these objects by the construction 25 of parts shown in the accompanying drawings, in which Fig. 1 is a plan of a shoe heel with one side shown in section to disclose the application of the washer through which the retaining nails are driven. Fig. 2 30 is a sectional plan of the upper layer of the rubber heel taken on the line 2—2 of Fig. 3. Fig. 3 is an elevation of a heel, partly in section, as it is attached to a shoe. Fig. 4 is a plan, and Fig. 5 is a perspective 35 of the washer through which the shoe nails are driven.

Similar reference characters indicate similar parts throughout the several views.

In the accompanying drawing 1 represents the rubber heel as it is secured to the 40 lifts 9 of a shoe, outlined at 10. To carry out my invention I imbed a thin soft metal plate 3 into the rubber heel a short distance from its upper surface, as indicated 45 in Figs. 1 and 3, this plate having small holes 8 through it for the passage of the nails 4. The part 2 of the rubber heel, between the plate 3 and the lifts 9 of the shoe heel, is punctured with large, square 50 openings 5, having partitions 7 between them, and in position so that the metal plate or washer will be lodged in the heel

with the nail holes centrally located relative to said openings, so that when a rubber heel is placed upon the lifts of a shoe and 55 the nails 4 are passed through the nail holes 6 and driven into the lifts 9 the plate 2 will be drawn or bent through the openings 5 and clamped firmly between the head of the nail and the lower surface of the lower 60 lift 9, which being firm and hard will hold the plate securely in place, as indicated at 4 in the cut away part, A, of the rubber as shown in Fig. 3, and this bending and 65 secure clamping of the plate so compresses the edges of the partitions 7 that any possibility of an opening appearing between the upper surface of the rubber heel and the lower surface of the heel lift is thereby 70 eliminated.

When placing these heels upon a boot or shoe the nail that passes through the opening at the back of the heel should be driven first to insure the proper placing of the back of the heel; then the two corner, or 75 outside nails, at the front of the heel, should be driven. This for the purpose, first, of properly locating the rubber heel upon the shoe, and, second, to insure the greatest possible strain upon the plate 3 when the 80 nails are driven, thus drawing the rubber surface as snugly and firmly as possible upon the leather lifts that form the upper part of the heel. It will be readily understood that with the metal plate 3 bearing 85 upon the hard surface of the sole leather lifts 9, it will be impossible for the nail to be forced any further inwardly and thus, possibly, injuring the heel of the wearer of 90 the shoe.

Having thus fully described my invention, what I claim as new in the art, is:

1. In combination with a rubber heel having a soft metal plate molded therein near the upper face of the heel, the sheet 95 of rubber above said plate having large openings therethrough from said plate to the outer surface, forming partitions between said openings in such a manner that the driving of nails through the sheet metal 100 plate into the lifts of a shoe heel will bend the metal plate through the said openings and press the partitions firmly against the surface of the lift thus holding the rubber

heel firmly upon the lifts and preventing the further advancement of the nail into the heel of the shoe.

2. In combination with a rubber heel having a perforated soft metal plate vulcanized into the rubber near its upper surface, the sheet of rubber above the metal plate having large openings therethrough adjacent to the perforations in the plate,

partitions between said openings, said openings and partitions being immediately over said plate and between said plate and the heel lifts upon which the rubber heel is planted, and means for securing said plate to said heel lifts through the perforations therein. 10 15

Signed at Grand Rapids, Michigan, November 27, 1923.

ALBERT E. PECKHAM.
